ARTIFICIAL LEG

Kostandean Marean, Dayton, Ohio

Application March 25, 1946, Serial No. 656,890

3 Claims. (Cl. 3-2)

1.

This invention relates to an artificial leg, and the main object of the invention is to provide an artificial leg which functions in substantially the same manner as a natural leg, thereby enabling the wearer thereof to walk or to be seated in a natural manner.

A further object of the invention is to provide an artificial leg in which adjacent sections thereof are connected by freely moving pivoted joints and are yieldably retained in their normal relative positions.

A further object of the invention is to provide an artificial leg in which the yieldable resistance to the relative movement of the adjacent sections is adjustable.

A further object of the invention is to provide an artificial leg in which the pivoted connections between adjacent sections and the parts co-operating therewith are arranged in the interior of the leg.

A further object of the invention is to provide an artificial leg which will not interfere with the flexing of the torso of the person wearing the same.

Other objects of the invention may appear as the leg is described in detail.

In the accompanying drawings Fig. 1 is a vertical section taken centrally through an artificial leg embodying the invention; Fig. 2 is a section taken on the line 2-2 of Fig. 1; Fig. 3 is a detail view of a portion of the adjusting device; and Fig. 4 is a detail view of the connection between the leg and the body of the wearer.

In these drawings I have illustrated one embodiment of my invention; but it is to be understood that the leg as a whole, as well as the various parts thereof, may take various forms without departing from the spirit of the invention.

In the illustrated form the artificial leg comprises four sections; an upper leg section 5; a lower leg section 6; a foot section 7; and a toe section 8. The several parts are connected one to the other by freely moving joints simulating the knee, the ankle and the toes of a person. Adjacent sections are yieldably retained in their normal positions in such a manner that they may be moved to substantially all positions to which a natural leg may be moved and when unrestrained will return to their normal positions.

The upper leg section 5 is adapted to be connected directly to the body of the wearer, and it is provided in its upper portion with a socket 9 adapted to receive the stump of an upper leg remaining after an amputation. This upper leg section is provided in its lower end with a cavity

2.

10, and the lower leg section 6 is provided in its upper end with a cavity 11 arranged in opposed relation to the cavity 10. Preferably, the upper end of the lower leg section extends into the cavity 10 in the upper leg section, the adjacent surfaces of the overlapping portions of the two leg sections being curved as shown at 12 to permit the free movement of the two sections with relation one to the other.

10. The upper and lower leg sections are connected one to the other by an anti-friction bearing rotatable about a substantially horizontal axis transverse to the leg. In the form here shown the bearing comprises an outer ball race 13 which extends into the recess 10 in the upper leg section and is rigidly secured to that section. The connection may be of any suitable character. As here shown a part, such as a strap 14 of U-shaped form, is arranged on opposed sides of the bearing and is rigidly secured to the outer race 13.

15. The looped upper end 15 of the strap has flat contact with the upper wall of the recess 10 and is apertured to receive a bolt 16 which extends through that portion of the upper leg section which is between the recess 10 and the socket 9. A nut 17 on the upper end of the bolt rigidly secures the latter to the leg section, which is preferably provided with a recess 18 to receive the nut and the upper end of the bolt and thus avoid any projection in the socket 9. The inner ball race 19 is secured to a short shaft 20 which is mounted in a U-shaped bracket 21 mounted in the recess 11, resting on the bottom of that recess and rigidly secured to the lower leg section

25. by a bolt 22 extending through that part of the lower leg section which lies between the recess 11 and a cavity 23 in an intermediate portion of that leg section. A series of balls 24 are arranged between the two ball races so as to permit the free relative movement of the two leg sections.

The upper and lower leg sections are yieldably retained in their normal relative positions, that is in substantial alignment one with the other, by suitable spring means. In the arrangement shown a coil spring 25 is secured to the upper leg section, within the recess 10, and is connected at its lower end with the lower leg section. This spring is of such tension that it will permit the relative movement of the leg sections on the bearing and will return the leg sections to their normal positions when the moving force has been relieved. It will be noted that the adjacent portions of the upper and lower sections, in the rear 50 of the leg, are cut away, as shown at 26 to permit

55 of the leg, are cut away, as shown at 26 to permit

the flexing of the knee and that the forward portions of the leg sections directly in front of the bearing are arranged to contact one with the other, as shown at 27, when the two sections are in their normal positions, thus positively limiting the forward movement which can be imparted to either leg section with relation to the other.

It is desirable that the yieldable connection between the two leg sections should be adjustable in order that it may be accommodated to the needs or preferences of the wearer. In the arrangement here shown the lower end of the spring 25 is connected, by a flexible element 28, with a rotatable member 29 mounted in the cavity 23. This flexible element may be of any suitable character but is preferably in the form of a flat strip of suitable material which is substantially nonextensible, such as thin metal or a suitable fabric. It will be noted that that portion of the leg section between the recess 11 and the cavity 23 is provided with an opening 30 through which the flexible element extends. The rotatable member 29 to which the strap or flexible element 28 is connected is preferably in the nature of a shaft extending transversely to the leg and rotatable in bearings 30 and 31 carried by the side portions of the leg. Preferably these bearings are carried by plates 32 and 33 rigidly secured to and preferably countersunk into the respective side walls and rigidly secured thereto. That wall of the cavity 23 adjacent the plate 33 is cut away to provide a relatively large opening 34, and this opening is closed by the plate 33. Rigidly secured to the shaft 29 is a ratchet wheel 35 which is engaged by a pawl 36 slidably mounted in a U-shaped bracket 37 carried by the plate 33 and extending into the cavity 23. A spring 38 retains the pawl in yieldable engagement with the ratchet wheel. The outer end of the shaft is provided with means whereby it may be rotated, such as a slot 39 adapted to receive the bit of a screw driver or other implement. Connected with the pawl 36 is a finger 40 which extends laterally through a slot 41 in the plate 33, so that the pawl may be actuated from the exterior of the leg. Preferably, the outer end of the finger is provided with a button 42 by which it may be moved. When the yieldable resistance to the relative movement of the leg sections is to be adjusted, the pawl is disengaged from the ratchet wheel and the tension of the spring will cause the strap 28, which is wound on the shaft, to rotate the shaft and the ratchet wheel and thus relieve the tension of the spring. The pawl is then released and permitted to again engage the ratchet wheel, and the shaft is rotated in a direction to wind the strap onto the shaft, the pawl then riding over the ratchet teeth and automatically locking the shaft in its adjusted position when the desired tension has been imparted to the spring.

The lower end of the lower leg section 16 is provided with a recess 43, and the foot section 7 is provided with a recess 44 opposed to the recess 43, and a bearing 45 similar to the bearing in the knee joint, is arranged in these recesses and connected with the respective sections by bolts 46 and 47, and yieldable means are provided to resist the relative movement of the foot and lower leg sections from their normal positions. This yieldable means is shown as a spring 48. The connections between the lower leg section and the foot section, to form the ankle joint, are substantially identical with the knee joint except that the spring 48 is arranged in the rear

of the bearing and is not adjustable. Obviously means could be provided for regulating the tension of the spring, if desired.

It is also desirable that the toe section 8 should be yieldable to permit the movement of the foot section on the ball of the foot. As here shown the toe section is separate from the foot section and is connected thereto by a hinge 49 secured to the adjacent bottom portions of the foot section and the toe section. The end surfaces of the two sections diverge upwardly, as shown at 50, and a coil spring 51 is interposed between the two sections within the recess formed between the same. Thus a forward tilting of the foot section on the ball of the foot, 52, and with relation to the toe section is permitted. Preferably, the upper end of the space between the toe section and the foot section is closed by a flexible covering 53 which does not interfere with the relative movements of those sections.

The leg is connected with the body of the wearer in such a manner that it may be manipulated by him and which will not interfere with the flexing of the torso either laterally or forwardly. For this purpose a link 54 is pivotally secured to the upper end of the upper leg section 5 at 55 and extends upwardly therefrom. In the present instance the upper portion of the link is bifurcated, and each arm 56 thereof is pivotally connected at its upper end to a flat loop or guide 57 adapted to receive a belt 58, by means of which the link, and therefore the leg, are secured to the body of the wearer. The pivotal connection 55 is on a transverse axis so that the body may be moved forwardly and rearwardly in relation to the leg, and the connections between the link and the belt are on a fore and aft axis to permit the lateral flexing of the body. I have shown a single link 54 for establishing such a connection, but it will be obvious that any suitable number of such connections may be provided.

The joints are preferably provided with a suitable covering 59 to close the spaces between the sections and prevent garments from entering the same. The covering may be of any suitable material, such as an elastic fabric. If desired, such a covering may be applied to the leg as a whole.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. An artificial leg comprising upper and lower sections having in their adjacent ends opposed cavities, each cavity having side walls, a front wall and an end wall, the side walls of the cavity in said lower section being arranged between the side walls of the cavity in said upper section, the front walls of said cavities being of less length than the respective side walls and being arranged to have abutting contact one with the other when said sections are in alignment, a bearing member within the cavity in said lower section and supported wholly on the end wall of the cavity in said lower section, a second bearing member mounted on the first mentioned bearing member for movement thereon about an axis transverse to said sections and secured to the end wall of the cavity in said upper section, and a spring connected with said sections to yieldably retain the same in alignment.
2. An artificial leg comprising upper and lower

sections having in their adjacent ends opposed cavities, each cavity having side walls, a front wall and an end wall, the side walls of the cavity in said lower section being arranged between the side walls of the cavity in said upper section, the front walls of said cavities being of less length than the respective side walls and being arranged to have abutting contact one with the other when said sections are in alinement, a bearing member within the cavity in said lower section and supported wholly on the end wall of the cavity in said lower section, a second bearing member mounted on the first mentioned bearing member for movement thereon about an axis transverse to said sections and secured to the end wall of the cavity in said upper section, said lower section having a second cavity below the cavity in the upper end thereof, and the end wall of the upper cavity in said lower section having an opening connecting the two cavities, an expansion spring within said upper cavity in said lower section and connected at its upper end with a fixed part of said upper section above the axis of said bearing members, a member connected with the lower end of said spring and extending through said opening at the end wall of said upper cavity, and means in said second cavity in said lower section for connecting said member with said lower section.

3. An artificial leg comprising upper and lower sections having in their adjacent ends opposed cavities, each cavity having side walls, a front wall and an end wall, the side walls of the cavity in said lower section being arranged between the

side walls of the cavity in said upper section, the front walls of said cavities being of less length than the respective side walls and being arranged to have abutting contact one with the other when said sections are in alinement, a bracket within said cavity in said lower section and mounted on the end wall of said cavity, a bearing member mounted on said bracket, said bracket constituting the sole support for said bearing member, a second bearing member mounted on the first mentioned bearing member for movement thereon about an axis transverse to said sections and mounted on the end wall of the cavity in said upper section, and spring means for yieldably retaining said lower section in alinement with said upper section.
